THREADING APPLIANCE

Frederic Nell, Waynesboro, Pa., assignor to Landis Machine Company, Waynesboro, Pa., a corporation of Pennsylvania

Application October 20, 1949, Serial No. 122,466

6 Claims. (Cl. 80—6)

This invention relates to tools or appliances for rolling screw threads and particularly to appliances for automatic machine tools wherein a pair of spaced threading rolls are mounted in a holder and are thereby fed laterally toward a rotating work piece.

This application is a continuation in part of my previous application Serial No. 762,581, filed July 22, 1947, now abandoned.

It is usual, in tools of this kind to employ threading rolls which are positively geared to rotate at the same rate of speed. The motive power is supplied by the frictional contact of the rolls with the power-driven work piece. The lateral feeding of such a thread rolling device, while useful in avoiding an axial feed which is sometimes impossible due to the nature of the work, has certain inherent difficulties which are not easily overcome. As shown in the patent to Gould, No. 2,257,234, issued September 30, 1941, the two rolls of such a device contact the work piece initially on a plane spaced from the central plane of the rolls which latter plane must be reached to finish the thread. In other words the rolls contact the work initially at points which are less than 180° apart on the circumference thereof. As the thread rolling operation progresses, this angle increases until it becomes 180° at which time the narrowest part of the opening between the rolls is reached and the thread is finished.

Therefore, the lateral relationship between the threads on the two rolls varies as the rolling operation proceeds and provision must be made to permit such variation. A resilient connection between the two rolls, such as that shown in the patent to Affleck, No. 2,355,132, issued August 8, 1944, is undesirable for the reason that failure of the rolls to assume their correct position before the start of an operation, for whatever reason, cannot be corrected after the operation has begun. This is due to the fact that such correction would have to be made by independent rotation of one roll, which is not possible. The system of permitting relative lateral movement between the two rolls while they are being driven at the same rotational speed, as shown in the aforementioned patent to Gould, is preferable because any initial error in the relative lateral positions of the rolls can be instantly overcome after the start of the rolling operation by the lateral movement of one of the rolls. Such prior devices are, however, expensive and must be very accurately manufactured to produce work pieces having accurate and uniform dimensions. Moreover, high production of threads is a necessity for such a device, and such mechanisms, even though initially constructed to a high degree of accuracy, will not long retain that accuracy under operating conditions. These objections to the prior devices I eliminate by the use of novel compensating mechanisms which permit accurate adjustment without sacrificing any of the essential rigidity of the tool.

Devices of this same general description have been provided with tapered or frustoconical rolls for the production of threads on tapered work pieces. In these prior tools, the tapered rolls are invariably mounted with their axes parallel so that the larger end of the roll operates upon the smaller end of the work and vice versa. Since rolls and work piece rotate at the same speed, such lack of proportion between adjacent diameters of work piece and rolls makes uniform surface speed of the contacting surfaces impossible. Undesirable slippage thus results between the surfaces of rolls and work piece at both ends and pure rolling action without slippage occurs

2

only at the lateral mid-point of the rolls and work piece. I have greatly improved the efficiency and increased the useful life of the rolls by mounting them on axes which are inclined to each other and to the axis of the work piece to a degree which will permit the larger and smaller ends of the rolls to operate upon the larger and smaller ends, respectively, of the work piece. Thus adjacent surfaces of rolls and work piece move at the same linear speed and pure rolling contact, without slippage, is obtained along the full length of the rolls and work piece, resulting in an improved product and longer roll life.

Since a thread rolling operation results in the generation of considerable heat, it is necessary to provide a supply of coolant to the rolls to keep their temperature at a relatively low level. Heretofore, such coolant has been directed indiscriminately over the whole area of operation and has had a cooling function only. I improve the operation of my tool by directing coolant through the interior of the tool to the surface of each roll individually. This concentration of the coolant flow, besides simplifying the piping of the complete machine and providing the necessary cooling effect, also effectively washes the surfaces of the rolls to remove particles of metal which constantly adhere thereto, leaving the roll surfaces properly clean and free of foreign matter destructive to the correct thread form on the work piece.

Automatic screw machines of the type to which my device is intended to be applied often provide a very limited amount of space in which the tool must move laterally from a rest position into operative position and return. In its rest position, the tool must be withdrawn far enough to permit the work to be indexed. In prior constructions, these considerations have severely limited the size of the tool and consequently, the size of the threading rolls, which should be made as large as possible to provide a greater amount of rolling surface and thus distribute the wear of the rolling operation over a larger area as well as provide for stronger supporting members. I have provided novel mechanism for further retracting the most obtrusive portion of the tool when it is in rest position and without any additional lateral movement of the shank or holder by which the tool is supported. By this means, the rolls and their supporting members, for any given size of work and machine, may be made larger than has heretofore been possible, with consequent increase in the useful life of the rolls and in the strength of the supporting members.

It is accordingly an object of this invention to provide, in a thread rolling appliance a novel combination of spaced rolls for relative lateral adjusting movement on the work piece and novel compensating mechanism to correct for taper or parallelism of the work piece and wear without sacrificing rigidity of the mechanism or accuracy of the work done.

Another object is to provide such a thread rolling device having novel mechanism of improved accuracy, rigidity and life for the adjustment of the space between the roll axes to effect adjustments in the diametrical size of the finished work piece.

It is a further object of my invention to provide an improved device for rolling tapered threads from a lateral direction, having rolls whose axes are inclined relative to the work axis to achieve equal surface speeds of rolls and work piece along the entire line of contact therebetween.

Another object is to provide an improved device for rolling tapered threads from a lateral direction, in which the larger ends of the rolls operate upon the larger end of the work and the smaller ends of the rolls operate upon the smaller end of the work.

A further object is to provide an improved thread rolling appliance in which a flushing coolant, is supplied individually to each roll from the interior of the device in novel manner.

A still further object of my invention is to provide a novel replaceable thrust bearing arrangement for absorbing the axial pressures induced in the rolls during the rolling operation.

Further objects and advantages of the present invention will be apparent from the following description thereof and from the accompanying drawings, in which

Figure 1 is a side elevation of a tool embodying my invention for rolling tapered threads and which is shown at the point of finishing a rolling operation upon a work piece,

Figure 2 is a side elevational view showing the opposite side of the tool shown in Figure 1 with the holder broken away in part;

Figure 3 is an end elevational view of the tool shown in Figure 1;

Figure 16 is a vertical sectional view taken substantially along line 16-16 of Figure 15;

Figure 17 is a side elevational view of the tool shown in Figure 15, taken from the side opposite thereto, and

Figure 18 is a horizontal sectional view taken substantially along line 18-18 of Figure 15.

Referring to the drawings, a preferred embodiment of my improved thread rolling tool for rolling threads on tapered work pieces is shown in Figures 1 to 14 inclusive thereof. This tool comprises a holder 30 which is adapted to be secured to a cam operated tool slide of an automatic screw machine (not shown), for example, which slide moves in a path perpendicular to the axis of the rotating work piece. A frame 32 is supported by holder 30 in a manner to be described later and in turn rotatably supports a pair of threading rolls 34, 36. The pitch diameter of each roll is approximately an integer multiple of the pitch diameter of the thread to be rolled. In this illustrative embodiment this multiple is taken as 4. Consequently, each of the rolls 34, 36 is provided with a four start thread, the form of which is the inverse of the form of the thread to be produced.

To minimize slippage between the rolls and the work piece, the rotational speeds of rolls and the work piece must be a constant ratio at all points along the length of the thread. Since the rolls are driven by contact with the work piece and since the relative speeds of rolls with the work piece are inversely proportional to the respective diameters thereof, a constant speed ratio at all points along the length of the thread is impossible with the prior roll structures. I eliminate this prior disadvantage by tapering rolls 34 and 36 suitably with their smaller diameter ends in contact with the smaller diameter end of the work and with their larger diameter ends in contact with the larger end of the work. In the form shown the sine of the angle of taper of each roll is four times the sine of the angle of taper of the work piece. With this combination of diameters and taper and by reason of the fact that the large and small ends of the rolls 34, 36 are located so as to operate respectively on the large and small ends of the work piece, the elements of the cones of rolls and work piece will, if extended, meet in a common apex. Thus, equal peripheral speeds of work piece and rolls are assured at all points along the length of the thread.

As shown most clearly in Figures 4 and 7, rolls 34 and 36 are positioned in an open space 38 in the interior of frame 32 and are rotatably journaled upon a pair of sleeves 40 and 42 respectively. Sleeves 40 and 42 and rolls 34 and 36 are supported by a pair of spindles

44 and 46 respectively which pass through the sleeves.

A separable plate 48 (Figures 3 and 4) is secured to one side of frame 32 by means of screws 50. Both spindles 44 and 46 are similarly mounted, partially in frame 32 and partially in plate 48. Taking spindle 44 for example, this spindle is provided near one end thereof with an enlarged diameter portion 52 (Figure 4) which has a bearing simultaneously in aligned bores in plate 48 and frame 32. The opposite end of spindle 44 is journaled in a bushing 54 located in a suitable opening in frame 32. Spindle 44 is mounted with its axis inclined relative to the central horizontal plane of the tool, which plane contains the axis of the work, so that the periphery of tapered roll is properly inclined relative to the periphery of work piece. The angle between axis of work piece and axis of spindle 44 in this case therefore is one-half the included angle of taper of the work piece plus one-half the included angle of taper of the roll. The spindle 46 is mounted with the same inclination in the opposite direction.

At its end journaled in plate 48, spindle 44 is provided with a further enlarged head portion 56 which seats with provision for limited universal movement in a counterbore 58 in plate 48. As seen in Figure 1, a wrench socket 60 is formed in the head portion 56 for the manual rotation of spindle 44. Socket 60 is eccentric relative to head 56 by a few thousandths of an inch. This eccentricity is exaggerated for illustrative purposes in this figure. The central portion 62 of spindle 44 is formed concentrically with socket 60 and hence also eccentrically relative to portions 52 and 56. The end portion 64 of spindle 44 which is journaled in bushing 54 is formed concentrically with portions 52 and 56 and eccentrically relative to central portion 62.

Manual rotation of spindle 44, as by means of a wrench inserted in socket 60, will have the effect of altering the position of the central portion 62 of spindle 44 relative to the horizontal central plane of the tool. By such rotation the periphery of roll 34, which is supported by portion 62, may be moved nearer to or farther from the axis of the work. This, together with the identical mounting of spindle 46 permits precise adjustment for the rolls 34, 36 to roll the desired size of thread.

As best seen in Figure 13, spindle 44 is provided with a peripheral groove 66 adjacent to head 56. The inner sloping side of groove 66 is engaged by the head of a screw 68 which is passed through plate 48 and threaded into the side of frame 32. Thus screw 68 serves to hold spindle 44 in correct axial position and, at the same time, to maintain any previously set rotary adjustment of said spindle. Notch 70 (Figure 1) is formed in the head 56 to permit the insertion and removal of screw 68. Graduations 72 are inscribed on the exterior surface of head 56 in order to provide, with a suitable index mark 74 on plate 48, a means of conveniently measuring the rotary adjustment of spindle 44. These details also are duplicated for spindle 46.

The above-mentioned bushing 54 is provided with an enlarged flange portion 76 (Figure 4) which is seated in a suitable counterbore in frame 32. The opening through bushing 54 which receives end portion 64 of spindle 44 is formed eccentrically relative to both outer diameters of the said bushing (Figure 2). Again, the amount of this eccentricity is exaggerated on the drawing for illustrative purposes. As a result of this eccentricity, rotation of bushing 54 will alter the position of end portion 64 of spindle 44 relative to the axis of the work. Since this alteration in position affects only one end of spindle 44, rotation of bushing 54 therefore provides fine adjustment of the inclination of spindle 44 and therefore of the taper of the thread to be formed.

Such adjustment must, of necessity, be very small in order to prevent the binding of spindle 44. It will be noted that bearing portion 52 of said spindle is made quite narrow for the same purpose, and is relieved by an adjacent tapered portion. The end portion 64 is likewise beveled as at 80, thus keeping the actual bearing surfaces of spindle 44 to a minimum.

A pair of openings 82 (Figure 2) are provided in flange 76 for the manual rotary adjustment of bushing 54 by the use of a suitable spanner. Graduations 84 on flange 76 and index marks 86 on frame 32 are provided to measure such adjustment. As seen in Figures 2 and 4, the outer edge of flange 76 is beveled for at least 180°

for engagement by the head of a screw 88 threaded into frame 32 adjacent the periphery of flange 76. Thus screw 88 maintains both the axial and the adjusted rotary positions of bushing 54. The above described taper adjustment is also duplicated for spindle 46.

These adjustments of diameter and taper provide distinct advantages not heretofore obtained in a device of this type. They make possible the production of threaded parts having precise accuracy as to diametrical size and taper. Furthermore they provide a means of maintaining such accuracy in spite of wear which is normally experienced due to the rotation of the rolls. Finally, the wear members, bushings 40 and 42 may, when badly worn, be replaced at little expense.

Inwardly adjacent the enlarged bearing portion 52, (Figure 4) sleeve 40 is formed with a flange 90 which serves as a thrust bearing for a bevel gear 92 (Figures 4 and 5) which is journaled for rotation upon sleeve 40. The inwardly facing end of bevel gear 92 is provided with a pair of lugs 94 which extend therefrom into a pair of openings 96 formed in the adjacent end surface of roll 34. By this means roll 34 and gear 92 are slidably keyed together for unitary rotation. A similar gear 98 is journaled upon sleeve 42 and is similarly keyed to roll 36. These gears 92 and 98 are connected by a series of meshing bevel gears 100, here shown as three in number (Figure 5). Thus rolls 34 and 36 are connected for positive unitary rotation. The pitch cones of gears 92, 98 and 100, rolls 34 and 36 and the work piece all have a common apex. Thus a pure rolling movement, without danger of slippage, is assured between rolls and work piece. The small amount of taper adjustment described above, while affecting this theoretical relationship actually need not be large enough to be considered from this aspect, except that it may be necessary to reduce the tooth thickness of the bevel gears slightly from the standard.

Each of the idling bevel gears 100 is similarly mounted. As shown in Figures 5 and 6, gears 100 are positioned in openings 102 in a side surface of frame 32. The typical gear 100 (Figure 6) is mounted on a flanged bushing 104 which is in turn journaled on a pin 106. Pin 106 is formed with an integral threaded portion which is threadedly engaged in plate 48 and from which pin 106 extends through bushing 104 into an opening 108 in frame 32. Since it is necessary, at least initially, to rotate one roll relative to the other for the purpose of obtaining the proper synchronism between the lateral positions of the threads on the rolls, one of the openings 102 is enlarged as at 110 so that one gear 100 may be readily removed and replaced.

It is well known in the art that the tooth-and-gap relationship between the two rolls at the points where they contact the work piece varies as the work blank W proceeds inwardly between the rolls from the dotted line position in Figure 1 until its axis lies in the plane containing the axes of the rolls as shown in the full line position, Figure 1, at which point the operation is completed. Since my rolls are positively geared together, no difference between them in rotational speed is possible. Therefore, the variation in their tooth-and-gap relationship must be compensated for by axial movement of the rolls. If both rolls are permitted to move axially during the rolling operation, they tend to move in opposite directions. To achieve some definite starting position, I, therefore, prevent one roll from moving axially. This fixed roll will then take the heavier portion of the stress of rolling and will actually roll the thread to a slight degree in an axial direction. The free roll will necessarily be required to move twice as far axially as it would move if both rolls were free.

In the embodiment shown I have confined roll 34 against axial movement. To avoid excessive wear on the sides of the opening 38 in which the rolls rotate, a replaceable thrust bushing 112 (Figure 4) is provided for roll 34. This bushing surrounds the hub of bevel gear 92 and has a flange which extends between the end face of roll 34 and one side of the opening 38. As shown in Figures 9 and 10, pins 114 are embedded in suitable openings in the side of opening 38 and extend outwardly therefrom to engage corresponding notches 116 in the circumference of bushing 112 to key said bushing against rotation. A similar thrust bushing 118 (Figure 4), similarly mounted and keyed, is provided for roll 36. The flange of bushing 118 is made somewhat thinner than the

flange of bushing 112 to allow space for the required axial movement of roll 36 during the rolling operation.

At the opposite end of roll 36, a thrust plate 120 is mounted in a suitable counterbore in the side of opening 38. Plate 120 surrounds spindle 46 but is in clearance relation thereto. As seen in Figures 12 and 14, pins 122, embedded in frame 32, extend therefrom to engage notches 124 in the circumference of thrust plate 120 to prevent rotation of said plate. Openings 126 are formed in frame 32, adjacent to and co-axial with bushing 130. Compression springs 128 (Figure 12) are positioned in openings 126 and are held in compression between the flange of eccentric bushing 130 and one side of thrust plate 120. Thus thrust plate 120 is resiliently held against the side face of roll 36 and said roll may move resiliently toward the left (as seen in Figure 4) against the pressure of spring 128, the counterbore in which plate 120 is mounted being made deep enough to accommodate such movement.

20 A similar thrust plate 132, similarly mounted and keyed is provided for roll 34 with the difference, however, that no springs are provided and said plate 132 fits snugly between the end face of roll 34 and frame 32 with no provision for axial movement of said roll.

25 Thrust members 112, 118, 120 and 132 provide an economical means of maintaining the original accuracy, since any or all of them may be replaced after wear at little cost. In prior constructions, in which such replaceable thrust bearings are not provided, it is necessary, if 30 the effects of wear are to be removed, to replace the much more expensive frame of the tool.

The entire assembly of frame, rolls, gears, etc. described above is mounted for pivotal movement in holder 30, the two arms 134 and 136 (Figure 6) of which 35 extend along opposite sides of the assembly. Referring particularly to Figure 6 it will be seen that a pivot pin 138 is threadedly engaged in the side of frame 32 and extends outwardly therefrom through a suitable opening in arm 134. A second pivot pin 140 having an enlarged head 142 is passed through arm 136 and is received in a suitable bore in plate 48. Pin 140 is retained in position axially by screws 144 which pass through head 142 and are engaged in threaded holes in plate 48. Thus since pins 138 and 140 are co-axial, the frame 45 assembly is mounted for limited rocking movement on holder 30 and about said pins as centers.

In the withdrawal of the tool laterally away from a finished thread it is necessary for the roll 34 also to move laterally due to the helical advance of the thread which 50 is now fully formed on the work piece. To make this movement possible, provision is made for the lateral movement of frame 32 and all associated parts, on pins 138 and 140 between the two arms of the holder 30. A spring 146 (Figure 6) located in an opening 148 in the side of frame 32, and a detent 150 associated therewith holds the frame assembly resiliently away from arm 134 and against arm 136. The lateral movement of roll 34 and the withdrawal movement is communicated to frame 32 which moves toward arm 134, compressing 55 spring 146.

As shown in Figure 7 my improved tool also comprises provision for a supply of coolant to each roll individually. A tube 152 is positioned within a vertical bore 154 in frame 32, the ends of which bore are sealed as by plugs 156. An internally threaded opening 158 is provided, leading diagonally into tube 156 from the exterior surface of the frame 32. In operation opening 158 is connected to any convenient supply of cleansing coolant which is fed through tube 152 and the openings 160 therein to points adjacent the threading rolls 34, 36. I have found that directing coolant in this manner to each roll, besides providing the desired cooling effect, serves the very useful purpose of cleansing the surfaces of the rolls of particles of metal which adhere thereto 70 and carries such particles into the coolant sump, leaving the roll surfaces properly clean for the rolling of finely finished threads.

The side of frame 32 which is to be positioned toward the chuck of the machine on which the tool is used, is recessed at 162 to receive arm 134 of holder 30 (Figures 2 and 6). By this means arm 134 does not protrude much beyond the surface of frame 32 permitting working close to the chuck to avoid bending the work. The limits of the rocking movement of frame 32, described above, are set by the contract between the bev-

led surfaces 164 and 166 with the adjacent surfaces of recess 162.

To minimize wear on the threading rolls and thereby to increase their useful life, they should be made as large as possible. Size is limited by conditions under which the tool is to be used and particularly by the path of the work piece as the indexing head of the machine carries said work piece into position to be threaded. In Figure 8, the reference character W indicates the work piece and the broken line 168 represents the path of a point on the circumference of the work W as it is moved into position for the thread rolling operation. Any tool used on the machine, therefore, must withdraw to the right of line 168 while the work indexes. I have accordingly provided a tension spring 170 which is connected (Figure 3) at its opposite ends to pins 172 and 174 which are embedded respectively in plate 48 and arm 136 of holder 30. When the tool is at rest the frame assembly is rocked about the pivots 138 and 140 by the tension of spring 170 to the position shown in Figure 8. This permits the forward part of the tool to clear the work path 168 with a minimum withdrawing movement.

When the tool moves horizontally forward to roll a thread on the work W, roll 36 comes into contact with the work first and this contact, in the continued advance of the tool, causes the frame assembly to be rocked into an upright position, extending the spring 170. The broken line 176 in Figure 8 indicates the position which frame 32 would assume in the rearmost position of the tool if spring 170 were not used. It is apparent from the intersection of lines 168 and 176 that with the same withdrawing movement and without my improved mounting, the tool would not clear the work path and would have to be made smaller, with consequent loss of working surface on the rolls and with weaker spindles.

The embodiment of my invention as adapted for rolling parallel (non-tapered) threads which is illustrated in Figures 15 to 18 inclusive is generally similar to the tool already described with specific differences to be set forth below. Similar parts are designated by the same reference numerals used for corresponding parts of the tool for rolling threads on tapered work pieces.

The essential difference in this modification of my invention is that the axes of work piece, threading rolls and connecting gears do not converge to a common point but are disposed parallel to each other. Instead of bevel gears, spur gears are used. Otherwise, all the improvements, adjustments and advantages of the tapered thread rolling device are present here also. One other difference is the substitution of a single pivot pin 178 for the two pins 138 and 140. This pin 178 passes completely through both arms 134 and 136 of holder 30 and through the frame 32 and plate 48 between them. The axial position of pin 178 is maintained by the provision of an integral collar 180 thereon, externally of arm 136 of holder 30. Collar 180 is engaged by the head of a screw 182, threadedly engaged in arm 136 and serving simultaneously to hold pin 178 in correct axial position and to lock it against rotation. This construction is preferable to the use of two pins where space permits.

The invention may be embodied in other specific forms without departing from the spirit or essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. An appliance for rolling screw threads by movement laterally onto a work piece comprising a holder for mounting said appliance in a machine tool; a frame member mounted in said holder; a pair of spindles rotatably mounted in said frame member each having two concentric end portions and a central portion eccentric thereto; a first pair of bushings surrounding said eccentric central portions of said spindles, eccentric bushings supporting corresponding end portions of said spindles rotatably mounted in said frame member for independent adjustment relative to the respective spindles, the other end portions of said spindles having means permitting universal rocking motion thereof relative to said frame

member; a first threading roll mounted on one of said first pair of bushings; thrust members for preventing axial movement of said first threading roll, a second threading roll mounted on the other of said first pair of bushings, a thrust member for limiting axial movement of said second threading roll in one direction, a second thrust member, and means resiliently urging said second thrust member and said second threading roll in said one direction.

10 2. An appliance for rolling screw threads comprising a holder for mounting said appliance in a machine tool; a resiliently biased frame member pivotally and slidably mounted in said holder; a pair of spindles rotatably mounted in said frame member each having two concentric end portions and a central portion eccentric thereto; a first pair of bushings each surrounding said eccentric central portion of one of said spindles; a pair of eccentric bushings each supporting one end portion of one of said spindles in said frame member and mounted for rotative adjustment relative to the spindle to adjust the spindle axes angularly relative to each other; means for securing said bushings in adjusted position relative to the respective spindles and frame member; a first threading roll mounted on one of said first pair of bushings, replaceable thrust members surrounding spaced portions of one of said spindles and having thrust receiving surfaces engageable, respectively, with the opposite ends of said first threading roll and additional surfaces engageable with said holder for preventing axial movement of said first threading roll; a second threading roll mounted on the other of said first pair of bushings; a replaceable thrust member surrounding the other of said spindles and having a thrust receiving surface engageable with one end of said second threading roll and an additional surface engageable with said holder for limiting axial movement of said second threading roll in one direction; a replaceable thrust member encircling a portion of said other of said spindles and having a radial face engageable with the opposite end of said second threading roll; and resilient means mounted in said holder for urging said last-mentioned replaceable thrust member and said second threading roll axially in said one direction.

3. An appliance for rolling screw threads by movement laterally onto a work piece comprising a frame structure, a pair of spindles; bearing portions on each of said spindles for mounting said spindles in said frame structure for rotational movement; a roll supporting portion on each of said spindles eccentric to said bearing portions whereby the distance between the axes of said rolls may be varied by rotation of said spindles; independent manually actuated frame bearings for one of said spindle bearing portions on each of said spindles, and means mounting said bearings for eccentric movement with respect to said frame to vary the relative inclination of the axes of said rolls.

4. In a thread rolling appliance having a frame and a pair of peripherally opposed threading rolls adjustable relative to each other; adjusting means for said rolls comprising individual supporting spindles for said rolls each having opposite end portions eccentric to the threading roll axis mounted for rotation with respect to said frame for independent adjustment of the spindles about the axis of said end portions to variably space the threading rolls from each other for operation upon work pieces of different sizes, said eccentric end portions at corresponding ends of the spindles being constructed to permit angular rocking movement of said portions relative to the spindle axes, and bushings journaling the other eccentric end portions of said spindles rotatably mounted in the frame in eccentric relation to said other end portions of the respective spindles for adjustment relative thereto to angularly position said spindles and threading rolls with respect to each other.

5. A thread rolling appliance as defined by claim 4, together with a gear train mounted in said frame drivingly connecting the threading rolls with each other for rotation at equal speeds.

6. In a thread rolling appliance having a frame and a pair of peripherally opposed threading rolls adjustable relative to each other; adjusting means for said rolls comprising individual supporting spindles for said rolls each having opposite end portions eccentric to the threading roll axis, the eccentric portions at corresponding ends of the spindles being rotatably mounted in said

frame, bushings rotatably mounted in said frame, said bushings having eccentric bores for supporting the other eccentric end portions of said spindles whereby upon rotation of said bushings the spindles may be angularly positioned with respect to each other and upon rotation of said spindles the axes of the thread rolls may be variably spaced from each other for operation upon work pieces of different sizes.
